UNITED STATES PATENT OFFICE.

EMIL W. R. KUGEL, OF BENEDICT, NEBRASKA.

CANNING APPARATUS.

1,390,142.

Specification of Letters Patent. Patented Sept. 6, 1921.

Application filed March 18, 1921. Serial No. 453,506.

To all whom it may concern:

Be it known that I, EMIL W. R. KUGEL, a citizen of the United States, residing at Benedict, in the county of York and State 5 of Nebraska, have invented certain new and useful Improvements in Canning Apparatus, of which the following is a specification.

This invention relates to apparatus for canning and preserving in accordance with 10 what is known as "the cold pack process."

The object of the invention is to provide a simple, cheap and efficient cooker of this character which is composed of a minimum number of parts united so that there is no 15 danger of them being displaced thereby insuring proper positioning of the food containers at all times without necessitating any adjusting of the cells.

With these and other objects in view, the 20 invention consists in certain novel features of construction as hereinafter shown and described and specifically pointed out in the claims.

In the accompanying drawings:

25 Figure 1 represents a longitudinal vertical section through a cooker constructed in accordance with this invention.

Fig. 2 is a transverse section thereof with a container shown in dotted lines therein.

30 Fig. 3 is a detail plan view of the cooker, and,

Fig. 4 is a detail perspective view of two of the intersecting cell-forming strips or partitions.

35 The cooker constituting this invention preferably comprises a metallic vessel 1 preferably constructed of sheet metal such as galvanized iron and which is here shown rectangular in configuration although obvi-

40 ously it may be of any other desired shape.

This vessel 1 is provided at its upper end with an inturned flange forming a reinforcing bead 2 at the open end thereof and is equipped with a removable closure 3 having

45 a downturned flange 4 fitting snugly around the outer face of the vessel 1 in substantially watertight relation. This top or closure 3 is provided with a plurality of steam outlet apertures or perforations 5 as shown in Fig.

50 1, both the vessel and the top being equipped with suitable handles to facilitate lifting thereof and the removal of the top.

Within the vessel 1 is provided a cellular structure comprising a series of intersecting 55 sheet metal partitions 6 and 7 which may be of any suitable or desired width and are

equipped, respectively, with transversely extending slots 6^a and 7^a one opening through the lower edge of one strip and the other through the upper edge of the other strip so that when the strips are assembled they will interlockingly engage to hold them in planes at right angles to each other, the strips 6 and 7 in Fig. 4 being shown arranged in juxtaposition ready for assembling, the slot 6^a in strip 6 opening through the lower edge thereof, while the slot 7^a in strip 7 opening through the upper edge. The free ends of the strips 6 and 7 are equipped with right angularly extending 70 attaching flanges 8 which bear against the opposed side walls of the vessel and are secured thereto by soldering, riveting or otherwise, the structure comprising these strips being preferably arranged about midway 75 the height of the vessel although obviously it may be disposed at any desired height therein. The cells 9 formed by this structure are designed to receive the food containers indicated in Fig. 2 by dotted lines which 80 are usually in the form of glass jars having screw tops such as are commonly known in the canning and preserving art.

Extending from one end to the other of the vessel 1 on the bottom thereof are a plurality of metal strips 10, six being here shown and each provided with a plurality of upstruck container supports 11, each strip having four as is shown clearly in Fig. 2 to provide one for each of the cells 9, there being twenty-four cells in the receptacle or vessel 1 herein shown, six in each series extending longitudinally of the vessel and four transversely thereof. These strips 10 extend transversely of the vessel 1, as is shown 90 clearly in Figs. 2 and 3 with an upstruck support 11 positioned centrally at the bottom of each cell 9 to receive and support the container and hold it out of contact with the bottom proper of the vessel 1 to avoid all 95 danger of breaking of the receptacle when the contents become heated and to permit the free circulation of the water used in the vessel 1 around the containers. The portions 12 between the supports 11 extend under the longitudinal partition strip 7 and are secured to the bottom of the vessel 1 by soldering or otherwise.

In the use of this apparatus the food to be canned or preserved is first packed in the 110 containers C and said containers are placed in the vessel 1, one in each cell 9 and sup-

ported on the upstruck strip portion 11. The vessel 1 is then filled with cold water and placed over a steady fire, it of course being understood that the top 2 is placed on the vessel before or immediately after the placing thereof over the fire. The water in the vessel 1 is brought slowly to a boil and allowed to continue to boil for a predetermined time sufficient to thoroughly sterilize 10 the contents of the containers C. After they have been sterilized the tops are placed thereon and screwed down tight thereby excluding all air and effectively sealing the containers C so that the material therein 15 will be preserved indefinitely.

From the above description it will be obvious that the strips 10 and the cellular structure being permanently secured within the vessel 1, the only movable part is the top 20 3 so that all danger of displacement of the parts is obviated thus rendering the apparatus as simple as possible.

The preferred embodiment of the invention is disclosed in the drawings and set 25 forth in the specification, but it will be understood that any modifications within the scope of the claimed invention may be made in the construction without departing from the principle of the invention or sacrificing 30 any of its advantages.

I claim:

1. In a cooker of the class described, a vessel, a cellular structure mounted intermediate the top and bottom of said vessel, 35 a metal strip carried by the bottom of the vessel and having an upstruck portion arranged below one of the cells of said structure to form a container support and spacer.

2. In a cooker of the class described, a vessel having a plurality of cells with sheet 40

metal upstruck container supports mounted on the bottom thereof and comprising a metal strip resting flat against the bottom of the vessel and having spaced upstruck 45 container receiving platforms.

3. In a cooker of the class described, a vessel having a plurality of communicating cells with a metal strip extending across the vessel on the bottom thereof and having an upstruck portion located in each cell to form 50 a container support, the strip between said upstruck portion being secured to the bottom of the vessel.

4. In a cooker of the class described, a vessel having a removable closure, a cellular structure mounted intermediate the top and bottom of said vessel and fixedly secured to the side walls thereof and metal strips secured to the bottom of the vessel and each having an upstruck portion arranged below 55 one of the cells of said structure to form a container support and spacer.

5. In a cooker of the class described a vessel having a removable closure with a cellular structure secured to the side walls 60 thereof intermediate its upper and lower ends, said structure being composed of a plurality of intersecting metal strips having interlocking slots in the lower and upper edges of the coöperating strips, and a plurality of metal strips mounted on and secured to the bottom of the vessel in spaced 65 relation and each having a plurality of longitudinally spaced upstruck portions, one of which is arranged below each cell of the 70 structure to provide a container support.

In testimony whereof I affix my signature hereto.

EMIL W. R. KUGEL.
